US0D1078544S

(12) **United States Design Patent** (10) **Patent No.:** **US D1,078,544 S**
(45) **Date of Patent:** **** Jun. 10, 2025**

(54) **MOTORCYCLE**

(71) Applicant: **Zhejiang LEQI Vehicle Co., Ltd.**,
Taizhou (CN)

(72) Inventor: **Dexiang Zhang**, Taizhou (CN)

(**) Term: **15 Years**

(21) Appl. No.: **29/920,718**

(22) Filed: **Dec. 12, 2023**

(30) **Foreign Application Priority Data**

Nov. 14, 2023 (CN) 202330742993.X

(51) **LOC (15) Cl.** **12-11**

(52) **U.S. Cl.**
USPC **D12/107**

(58) **Field of Classification Search**

USPC D12/107, 110, 111, 117; D21/432, 538
CPC B62K 11/00; B62K 11/02; B62K 11/04;
B62K 11/10; B62K 17/00; B62K 19/00;
